UNITED STATES PATENT OFFICE.

LOUIS BINDER, OF NEWARK, NEW JERSEY.

BOX.

Application filed July 29, 1921. Serial No. 488,290.

To all whom it may concern:

Be it known that I, LOUIS BINDER, a citizen of the United States, and a resident of Newark, county of Essex, and State of New Jersey, have invented certain new and useful Improvements in Boxes, of which the following is a specification.

This invention relates to an improved box, and particularly to boxes that are held shut by a brad or nail forced through the end of the lid into the front wall of the box.

The material of which cardboard boxes are made is brittle or pulpy and does not closely grasp a nail, and when the lid is pried open there is more likelihood of the cover being stripped from the nail than that the nail will be withdrawn from the box with the lid.

20 To overcome this defect I have devised the present box, which in the main is made of cardboard, but which has wooden or similar close grained material disposed at the edge of the front of the box and at the free end 25 of the lid to provide a nailing portion which can be repeatedly pried open and re-nailed, if necessary, without crumbling or tearing away of the material surrounding the nail.

The invention is illustrated in the accompanying drawing, in which Figure 1 is a perspective view of the box with the lid open, the usual ornamental covering being left off to more clearly show the construction. Figure 2 is a cross-section of the box 35 shown in Figure 1, but with the lid closed. Figure 3 is an enlarged section showing the front wall of the box proper and the front end of the lid with the covering sheet in position.

40 The box is made of heavy cardboard, the usual way of making these boxes being to make the bottom 10, the rear wall 11, the end walls 12 and the front wall 13 from a single blank and then bending up these side 45 walls and securing them in position by pasting or otherwise, and I provide at the top edge of the front wall a recess, into which I place a strip 14 of closely grained material, preferably wood, this strip being 50 held in position by glue or other suitable adhesive, and I prefer to make the ends of the recess into which the strip fits so that they converge, as at 15, whereby the recess

is narrower at the top than at the bottom and the strip is therefore more securely held 55 against displacement.

While the glue is usually sufficient to hold the strip against lateral movement, I prefer to provide an outside panel 16 of cardboard this being usually thinner than the material of the front wall 13 and fastened in place by glue spread over its entire inner face. The lid is usually fastened so that it is hinged to the top of the back wall 11, the normal way at present of doing this being 60 by pasting a strip 17 of linen or similar fabric to the rear wall of the box and also pasting it to the lid.

The lid is formed of a center sheet 18 of heavy cardboard, which sheet is made 70 shorter than the lid itself, and to complete the length of the lid I provide a wooden strip 19, and while wood is preferred, it will be understood that other closely grained material can be employed, if desired.

A top sheet 20 is pasted over the outer face of the center sheet 18 and the strip 19, so that the end of the strip 19 and the end of the sheet 20 define the end of the lid. A bottom sheet 21 is fastened, usually by pasting, to the center sheet 18 and overlaps the center sheet and projects over a material 80 space of the strip 19.

The sheet 21 thus performs a double function in that it assists in holding the strip 19 85 in place at the end of the lid, and also fits inside of the side walls of the box proper, thus preventing inward movement of the sides of the box to prevent damage to the contents, which might be caused by the collapsing or excessive inward movement of the side walls. I may also employ a sheet 90 22 pasted to the inside of the front wall of the box to give it strength.

These boxes are usually covered with an 95 ornamental or finishing sheet, usually paper printed to simulate wood or containing an advertisement of the goods enclosed, the sheet for the lid of the box being shown at 23 in Figure 3, the sheet covering the box 100 proper being illustrated at 24, Figure 3.

I have found, in ordinary cardboard boxes that when a brad is used and is forced through the edge of the lid down into the front wall of the box, the material of the 105 box separates easily when punctured edge-

wise, so that there is not a firm grip on the nail in many instances, and on the other hand, the material, when very dry, crumbles easily and has a tendency to have small pieces thereof detached therefrom, this quality causing the material of the lid, when made of cardboard, to give way when the lid is to be pried open, so that the cover rides off of the nail rather than the nail coming out of the side of the box.

In Figure 2 I show the brad 25, which, it will be noticed, in my form of box is nailed through the wooden strip on the lid and into the wooden strip of the front side of the body of the box. If the lid is to be opened it is usually pried by a box opener which is inserted between the lid and the top edge of the front of the box, and when pressure is applied the lid is pried open and takes the brad 25 with it, any pulling of the strip on the lid being resisted by the top sheet 20 being pasted over it and tending to hold it down, and the front edge of the bottom sheet 21 also being glued to the strip 19 and assisting in holding it in alignment with the center sheet 18, and furthermore I desire to make the strip 19 as long as the box lid so that the leverage applied by the box opener anywhere along the length of the strip 19 will not cause undue bending of the box lid, but the lid will be pried up, carrying the brad 25 with it, thus making it unnecessary to localize the prying open of the box close to the brad 25.

Furthermore, the bottom sheet 21 of the lid, fitting within the side walls of the box, braces these side walls when the lid is shut and also limits the inward movement of any

box opener so that such opener will not engage any of the goods to damage them.

I claim:

1. A box made of cardboard and having a cardboard lid, a wooden strip secured edge-wise in the top edge of the front side of the box, and a wooden strip secured edgewise in the free end of the lid.

2. A box made of cardboard and having a cardboard lid, a wooden strip secured edge-wise in the top edge of the front side of the box, and a wooden strip secured edgewise in the free end of the lid, said last mentioned strip being substantially as long as the lid.

3. A cardboard box with a cardboard lid, the front wall of the box having a recess with upwardly converging ends, a wooden strip fitted in said recess, a wooden strip as long as the lid and secured to the free end of the lid so that the wooden strips are in juxtaposition when the lid is shut.

4. A cardboard box with a cardboard lid, the front wall of the box having a recess with upwardly converging ends, a wooden strip fitted in said recess, the lid being formed of a center cardboard sheet, a top cardboard sheet, a bottom cardboard sheet, the bottom sheet fitting within the walls of the box, and a wooden strip secured between said bottom and top sheets and abutting on the center sheet, the outer edge of the strip and of the top sheet defining the edge of the lid.

In testimony that I claim the foregoing, I have hereto set my hand, this 28th day of July, 1921.

LOUIS BINDER.
